JOHN W. STEINMEYER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

HOPPER-DOOR MECHANISM.

1,109,602.

Specification of Letters Patent. Patented Sept. 1, 1914.

Original application filed December 17, 1912, Serial No. 737,236. Divided and this application filed August 21, 1913. Serial No. 736,043.

To all whom it may concern:

Be it known that I, JOHN W. STEINMEYER, residing at St. Louis, Missouri, and being a citizen of the United States, have invented 5 certain new and useful Improvements in Hopper-Door Mechanism, of which the following is a full, clear, and exact description, such as will enable others skilled in the art to which it appertains to make and to use 10 the same, reference being had to the accompanying drawings, which illustrate the preferred form of the invention; though it is to be understood that the invention is not limited to the exact details of construction 15 shown and described, as it is obvious that various modifications thereof will occur to persons skilled in the art.

In said drawings Figure 1 is a fragmentary side elevational view of a car equipped 20 with the present invention, parts being broken away to illustrate internal construction of the hopper. Fig. 2 is a vertical, transverse sectional view, the section being taken on line 2—2 of Fig. 1, through the hopper 25 and floor of the car, with the hopper door shown in solid lines in locked position and in dotted lines in unlocked position. Fig. 3 is a transverse, vertical sectional view, the section being taken on line 3—3 of Fig. 1, looking 30 in the direction indicated by the arrows, and shows a portion of the hopper in elevation, with a hopper door in open position. Figs. 4, 5 and 6 are details of construction 35 relating especially to means employed for supporting and operating the door. Fig. 7 is a vertical, longitudinal sectional view through one of the intermediate stringers, the section being indicated by the line 7—7 of Fig. 3.

40 My invention relates in general to the hopper of a grain car, or car adapted to carry lading of similar fine material, and specifically relates to the door construction and door operating mechanism employed, 45 other features of the construction forming the subject-matter of my pending application, Serial No. 737,236, filed December 17, 1912, of which this application is a division.

One object of the invention is to provide 50 a hopper, the drop door of which is held in locked position by the weight of the door,

assisted by a distributed lading, but which door may be released and will automatically swing to open position when so released.

I attain the above outlined objects, broadly, 55 by positioning transversely of and in juxtaposition to the side doors of the car a pair of hoppers, which hoppers are preferably constructed of a single sheet of metal, bent into hopper shape and securely braced to the 60 underframe elements. Adapted to extend transversely of and supported by the side and center sills is a pair of grain supporting doors, which when used to support grain are placed in horizontal position, but which 65 may be swung into vertical position to partially close the side doors, thereby uncovering the hoppers. The lower edge of the hopper opening has an upturned flange 70 adapted to support the lower side of a hinged drop door, which door is adapted to be lifted bodily by a toggle link to clear the flange so that the lading and weight of the door 75 will act to swing the same into open position.

My invention relates to other elements and 80 combination of elements and parts arranged to attain a well braced and readily constructed combined grain and box car, all as more fully hereinafter described and claimed.

While I have shown as a vehicle for my 85 invention a conventional form of car, it is, of course, to be understood that the invention is not specifically limited to this form of car but may be adapted to other forms with obvious mechanical modifications and 90 adaptations, and in the illustration but one hopper and its adjacent elements will be described in detail, it being understood that the similar elements are disposed in the corresponding position on the opposite side of the center sill.

Described more in detail I have shown one 95 of a pair of channel-shaped center sills A, which pair is connected by a center sill cover plate B, and spaced from which center sill is a conventional form of flanged or channel shaped side sill C. It will be noted that, as is usual with constructions of this character, the center sill is relatively deeper than the 100 side sill, but in this particular instance the top of the side sill is positioned slightly

higher than the top of the center sill, so that the grain door hereinafter described will be flush with the permanent car floor D when said grain door E is in its lowered position. 5 When in its raised position it will be understood that the door fits between the door posts F, which, together with the furring pieces G, form an outline for the grain door and constitute part of the side wall H. A 10 conventional cross-bearer J extends transversely of the car at each door post, between which cross-bearers and between the side sill and the adjacent center sill element is disposed the hopper K, particularly forming 15 a part of the subject-matter of this invention.

Paralleling the center and side sills and positioned substantially midway between the same and passing through the sides of the 20 hopper K, in a manner more particularly hereinafter described, and overlapping the cross-bearer is a longitudinally extending intermediate stringer L, Z-shape in cross section, the upper flange of which is nearly 25 flush with the top of the side sill C. Suitably riveted to the front face of the side sill and adjacent at the top thereof is an inverted reinforced L-shaped threshold plate M, which projects above the side sill a distance equal to the thickness of the door E, so that the top of the door E, when used as 30 a part of the floor, will be flush with the top of the threshold plate, as shown in Fig. 2.

The door E comprises a series of wooden 35 pieces 8, fastened together and reinforced by an intermediate wooden batten 9, bolted to the under or rear side of the door, each longitudinal edge of the door being bound by a metallic L-shaped batten 10, the upper 40 or inner batten 10 having a filler 11 disposed between one flange thereof and the door, so as to form with the batten a projecting flange or stop which, when this part of the door is resting on the center sill cover plate 45 B, will contact with the retaining piece 12 to prevent transverse movement of the door in one direction, the corresponding door on the opposite transverse side preventing movement in the other direction.

50 As the center sill is positioned below the plane of the car floor D a distance equal to the thickness of the retaining piece 12, and as the side sill is raised above the center sill this distance, the effect will be that the door 55 E when used as a part of the flooring will be in a substantially horizontal plane with one side of the door fitting in the angle between the threshold plate and the top of the side sill, resting on the side sill when in the 60 raised position shown in Fig. 3, or, the lowered position shown in Fig. 2. The inner side of the door is, of course, supported by the center sills and center sill cover plate, and is supported intermediate its width by 65 the intermediate stringer L. Each trans-

verse edge of the door is bound by a Z-shaped outstanding flanged plate 13 inset into the door, the projecting flange of which, as shown more particularly in cross section in Fig. 1, fits into a pocket or groove in the adjacent flooring D. 70

Referring to the hopper K, it will be noted that the body thereof is formed of a single sheet of metal bent into a three-sided hopper form, with an opening to the longitudinal side of the car below the door opening in the body portion of the car. The rear wall 14 of the hopper has its upper end bent horizontally to form an attaching flange 15, positioned between the top of the adjacent center sill element A, and the center sill cover plate B, and fastened to these members by means of rivets 16. This inside wall of the hopper is braced from the lower portion of the center sill by means of the angle bracket 7, having one end fastened to the lower flange of the center sill element and the other end upwardly angled to fit the inclined hopper wall. 80

Extending transversely of the car and adjacent each of the cross-bearers J, and positioned between the cross-bearer and the adjacent side plate 17 of the hopper K, are short transverse pieces 18 intermitted so as to permit the intermediate stringer L to pass therethrough. The outside end of the pieces 18 is inset in pockets 21 in the filler block 22, carried between the flanges of the side sill C, the end of the transverse piece fitting the upper portion of the channel and conforming in configuration to the underside of the upper flange of the side sill. 90

Each transverse side 17 of the hopper has its upper end bent outward to form a flange 23, which overlaps the transverse pieces 18 and is bolted or otherwise fastened to these pieces, as shown in Figs. 1 and 3. Each longitudinal front upper edge of the side sheet 17 of the hopper is bent inwardly toward each other to form flanges 24, which are bolted to the filler block 22 carried in the inside of the side sills. From this construction it will be seen that the side sill itself forms the upper front portion of the hopper and the hopper opening extends substantially from the bottom of the side sill to adjacent the bottom of the inside or rear wall 14. This inside or rear wall has an upturned flange 25 formed integral with a reduced extension 46 of the front flanges 24 adapted to support the door, as hereinafter described. 105

To brace the transverse sides 17 of the hopper above the door opening, to form a guide for the upper edge of the door and to form a chute for the lading in the vicinity of the channel of the side sill, there is positioned within the hopper a downwardly and inwardly inclined hood plate 27, each longitudinal end of which has an upturned 115

flange 28 fastened to the side of the hopper, the upper edge of the plate 27 being bent outwardly to fit beneath the lower flange of the side sill C, to which it is fastened 5 by any suitable means, such as the rivets adapted to hold the door bracket, herein-after described.

In order to close the portion of the sides of the hopper which were cut away in order 10 to insert the Z-shaped stringer L, there is disposed between each of the angles of the stringer a wooden filler 29 having an inclined face 30 (see Fig. 7) adapted to conform to the inclination of the side 17 of 15 the hopper. The portion of the side cut away to accommodate the stringer is bent to form an underlapping lip or flange 31 fastened to the underside of the transverse pieces 18, assisting to hold the two parts 20 thereof in position.

The hopper door Q is of a trapezoidal form and preferably formed of a flanged plate, which door when in closed position rests within the upturned flanges 25 and 46, 25 and is then positioned to the outer and underside of the hood plate 27 and positioned a distance from the side sill and its attached parts sufficient to permit the door to slide in its own plane a distance at least sufficient to uncover the flanges 25 and 46, as 30 shown in dotted and dashed line construction in Figs. 1 and 2.

The door is hinged to the side sills preferably by means of a pair of slotted hinges 33. The slot being in a plane parallel to the plane of the door permits the sliding movement hereinbefore referred to. In order to 35 actuate the door both to slide and swing the same positively either into its open position, shown in Fig. 3, or into the closed position, shown in Fig. 2, the mechanism described below is provided. Affixed to the side sill and to the underside of the horizontal outstanding flange of the hood plate 27 is a 40 centrally disposed bracket 34 carrying a pivot pin 35, to which is pivoted the upper ends of a pair of depending, freely swinging links 36. The lower ends of said links are connected by a pivot pin 37, which 45 constitutes the fulcrum for an actuating lever 38, one arm of this lever forming a bent handle 39 which extends outside of the side sill in all the positions it is caused to assume due to the position of the door. The 50 other end of the lever is pivoted by means of the pin 40 to the bracket 41, mounted centrally upon the under or outer face of the door Q.

Noting Fig. 3 it will be seen that actuating 55 the handle 39 will swing the door on its hinge 33 into position to close the hopper outlet, the arrangement of the links being such that the door is permitted to swing into the hopper until this upper portion 60 contacts with the hood plate 27. Then with

the pivot pin 34 as a relatively stationary pivot, the handle 39 is raised from the dot and dash position in Fig. 2 into the full line position shown in this figure, which has the effect of lowering the door from its dotted 70 position shown in this figure into its full line locked position. The handle is then locked in position by some suitable form of catch, lock or hasp passing through co-acting 75 apertures in the handle and an extension 47 from the bracket 34.

By this construction it will be seen that the weight of the lading carried by the door is supported by the flange 25 of the hopper itself and the weight of the lading is also 80 transmitted through the links and parallel lever 38, so that there is but little tendency for the door to open due to the weight of any lading above it, and at the same time there is afforded a means for readily moving the door into unlocked position so that the weight of the lading will tend to open the same, but in case of an ice seal the long handle will afford a material leverage to 85 positively open the door. 90

What I claim is:

1. A receptacle having an opening, a flange outlining a portion of said opening and extending substantially in the plane of the same, a door adapted to rest on said 95 flange to close said opening, and a door-supporting and actuating means adapted to raise said door from said angle to uncover said opening.

2. A receptacle having a bottom opening 100 therein, a door-supporting flange forming part of said receptacle, a door resting on said flange when closing said opening, and door actuating mechanism for lowering said door through said opening to uncover the 105 same.

3. A hopper including a downwardly inclined wall having an upturned lower flange, a pivoted door adapted to be supported by 110 said flange, and door actuating means adapted to raise said door to clear said flange.

4. A hopper having an outlet, a door supporting member outlining a part of said outlet, a pivoted door resting on said member, and door actuating means adapted to 115 slide said door from and to its position on said member.

5. In a car, a hopper having an opening in a side thereof, a door supporting member at one side of said opening, a door having one 120 side supported by a hinge connection and the opposite side supported by said member, and door actuating means for sliding said door into position to disconnect the same from said member. 125

6. In a car having an inclined opening, a support, a door for said opening, a slotted hinge connection between said support and door, and a door actuating lever for swinging 130 said door into closing position within said

opening and sliding said door into position, whereby the weight of the door will maintain the same in locked position.

7. In a car, a support, a drop door, a slotted hinge connection between said support and door, a lever having one end pivoted to the door, and a depending link pivoted in fixed position to the lever and support, said lever and link co-acting to lift said door into an unlocked, or lower said door into a locked position.

8. In a car, a hopper having an opening therein, a side sill, a door for said opening hinged to said sill, a bracket fixed to said sill, a link having one end supported from said bracket, and a lever fulcrumed to said link and pivoted to said door.

9. The combination with a hopper having an outlet in the bottom thereof, of a support, a drop door for said outlet, a slotted hinge connection between said door and support, and a door actuating mechanism adapted to raise said door through said outlet into position to be supported by a portion of said hopper.

10. A hopper having an opening, a closure therefor, a hood dispensed within said hopper outlining one edge of said opening, and

supporting means on said hopper for said closure co-operating with said hood to guide 30 the closure to a liberating position.

11. A hopper formed of a body portion comprising a plurality of hopper sheets, a portion of a side sill connecting two of said sheets, a hood plate adapted to guide a door 35 to a liberating position, and a door.

12. The combination with a side sill, of a hopper having an opening below said sill, a closure for said opening, and a hood plate fastened to said sill and overlapping said 40 opening and adapted to guide said closure to a liberating position.

13. The combination with a side sill of a hopper comprising a plurality of sheet sides and having an opening below said sill, a 45 door for said opening, and a hood plate fastened to said sill and to some of said hopper sheets and being adapted to guide said door to a liberating position.

In witness whereof I have hereunto set my 50 hand in the presence of two witnesses.

JOHN W. STEINMEYER.
